GAS FIRED BOILER

Uel R. Goodale, New Suffolk, N. Y.

Application January 23, 1940, Serial No. 315,214

3 Claims. (Cl. 122—161)

This invention relates to boilers of the type adapted to be used in connection with hot water or steam heating systems for residences and other buildings.

More particularly the invention relates to a gas-fired boiler of the character described.

One important object of the invention is to provide a novel construction of boiler of this type having walls of extreme thinness to insure efficient passage of heat from the fire space to the water within the boiler.

A second important object of this invention is to provide a novel boiler arrangement having corrugated walls which not only increase the heating area but also serve to reinforce the thin walls above mentioned.

A third important object of the invention is to provide an improved boiler having a novel arrangement of water legs and gas burner tubes, whereby the gases of combustion are caused to flow over the surfaces of the water legs in a manner to insure high efficiency of heat utilization.

A fourth important object of the invention is to provide a novel boiler construction, provided with improved fire leg and auxiliary air inlet means, so constructed as to cause the hot products of combustion to move in a relatively slow manner over the surfaces contacted by said portions, so that ample time is afforded for transmission of heat to the water within the boiler.

With the above and other objects in view, as will be presently apparent, the invention consists in general of certain novel details of construction and combinations of parts hereinafter fully described, illustrated in the accompanying drawings, and particularly pointed out in the appended claims.

In the accompanying drawings, like characters of reference indicate like parts in the several views, and

Figure 1 is a vertical diametric section through a boiler and its burner as constructed in accordance with this invention.

Figure 2 is a section on the line 2—2 of Figure 1.

Figure 3 is a section on the line 3—3 of Figure 1.

Figure 4 is an enlarged detail section on the line 4—4 of Figure 1.

Figure 5 is an enlarged fragmentary section showing the arrangement for connecting the inner and outer sheets of the inner water leg to form passages through the leg for products of combustion.

In the embodiment of the invention as here-

in shown, there is provided a base 10 which may be of circular form and from this base rises a set of vertical legs 11, which support a boiler bottom plate 12, the latter being secured to the legs in any preferred manner, such as welding, bolting or the like. The plate 12 is circular in form and has an upstanding peripheral flange 13, the purpose of which will be presently understood.

The boiler proper includes an outer sheet 14 of cylindrical form, and to the upper edge of the sheet 14 is welded or otherwise secured a top sheet 15. The sheet 14 is concentric to but spaced inwardly from the flange 13. Spaced inwardly from and concentric to the sheet 14 is an outer fire box sheet 16, which is provided with a series of vertically spaced and inwardly projecting corrugations 17 extending circumferentially of the sheet. The bottom edges of the sheets 14 and 16 are curved toward each other so that they meet and these meeting edges are welded together. The sheet 16 is of considerably less height than the sheet 14, and the space between these sheets forms an outer water leg 18. Welded to the upper edge of the sheet 16 and extending inwardly therefrom is an annular crown sheet 19. Depending from the inner edge of the crown sheet 19 is an inner fire box sheet 20, which is of less height than the sheet 16, and thus has its bottom edge spaced above the plane of the bottom edge of sheet 16. Spaced inwardly from the sheet 20 and concentric therewith is an inner boiler sheet 21, which is provided with vertically spaced corrugations 22 similar to the corrugations 17. The sheets 20 and 21 have their bottom edges bent to meet, and these bottom edges are welded together so that the space between the sheets forms an inner water leg 23. The sheet 15 is provided with a centrally disposed opening 24 and the sheet 21 projects through this opening and extends thereabove, the sheet 15 being welded at its opening to the sheet 21. It will now be observed that the space between the sheets 16 and 20 and below the sheet 19 forms an annular fire box. Arranged concentrically of the sheet 21 is a tube 25 of firebrick or other refractory material. The tube 25 is provided at its upper end with a peripheral flange 26 which engages on top of an annular filler piece 27, closing the space between the upper parts of the tube 25 and sheet 21 and having a peripheral flange 28 resting on the upper end of the sheet 21. Within the tube 25 is fitted a smoke pipe 29 having a bead 30 adjacent its upper end to engage on top of the upper

end of the tube 25 and thus prevent the smoke pipe from slipping down. Delivery pipes 31 lead upwardly from the top sheet 15 and return pipes 32 lead into the lower ends of the water leg 18. Suitable insulation 33 rests on the sheet 12 between the sheet 14 and flange 13 and extends upwardly to surround the sheet 14 and over the top of the boiler to abut against the upwardly projecting portion of the sheet 21. A wrapper sheet 34 serves to protect the insulation and hold it in place. Tubular passages 35 for the gases of combustion lead across the upper part of the inner water leg to conduct the gases from the fire box to the annular downcomer smoke flue 36, from whence the flow around the lower edge of the smoke pipe 29 passes up said pipe. A smoke box 37 covers the upper end of the pipe 29 and has a lower cylindrical wall 38 and a frustoconical top 39 having at its upper end a tubular smoke vent for attachment of the usual smoke pipe leading to a building chimney. The wall 38 has a series of air vents 40 formed therein, and below the smoke vent, there is located a baffle 41 supported from the wall 38 by brackets 42.

Fixed to the inner face of the sheet 21 at the lower part thereof are downwardly extending bolts 43 which pass through suitable openings adjacent the periphery of a damper plate 44 which is supported on the bolts by nuts 45. The nuts 45 serve to adjust the plate 44 toward and from the lower end of the water leg 23, so that the lower end of the space within the sheet 21 may close or may have gases or air admitted around the plate 44. The plate 12 is provided with a centrally disposed opening 46, and bolts 47 extend through this plate downwardly adjacent the periphery of said opening. These bolts pass through a damper plate 48 adjacent its periphery, and on the lower ends of the bolts 47 are adjusting nuts 49, by means of which the extent of opening for the passage of auxiliary air between the damper plate 48 and the sheet 12 may be regulated. The plate 12 collects condensate which flows into the damper plate and is drained therefrom through a tube 48a.

Flow pipes 50 connect the lower end of the leg 23 with the leg 18.

Extending inwardly from the legs 11 are removable pins or brackets 51, which support a gas ring 52. Burner tubes 53 of the general type shown in my prior patent, No. 2,170,139 extend up through the plate 12 and open toward the outer water leg. The ring 52 is supplied with a mixture of gas and air through a supply pipe 54 having at its free end a mixer 55 including a chamber 56 having one or more ports 57 for admission of air, the ports being controlled by the usual sliding shutter 58. The mixer is provided with an internally threaded opening 59, into which is screwed one end of a T-fitting 60, having the screwed-in end reduced and threaded so that a nozzle 61 having a screw kerf 62 or the like may be screwed therein and thus be interchangeable with like nozzles of different sizes. The opposite end of the T is normally closed by a pipe plug 63. The inlet 64 has connected thereto a gas line 65 interposed in which is a thermostatic control valve 66 of standard construction, and a standard cut-off valve mechanism 67 operating to shut off all gas supply if the gas from the burner pipes fails to light from any reason such as blowing out of the pilot light supplied through the branch pipe 68.

It will now be seen that upon the gas from the

burner pipes 53 being lit, the gases of combustion follow the course of the arrows, air being mixed with the gas at the main mixer 55, and auxiliary air being also admitted at the lower damper plate opening. The flow of the gases of combustion may take place solely through the passages across the inner water leg or may flow both through passages and through the space between the upper damper plate and the lower end of the inner water leg. The gases of combustion flow slowly over the boiler surfaces and gives up heat to the water covering the crown sheet and that in the water leg.

It will be noted from Figure 5 that the smoke passages are formed by dieing and punching the sheets 20 and 21, so that the died-out portion of sheet 21 is of conical form having a rolled or beaded edge 69, while the died-out portion 70 of sheet 20 engages beading and is welded to said bead.

What is claimed is:

1. A vertical cylindrical boiler including an outer sheet, a fire box sheet concentric to and spaced from the outer sheet, the fire box sheet and outer sheet being connected at their bottom edges to provide an outer annular water leg, a second fire box sheet spaced inwardly from the first fire box sheet and concentric therewith, an annular crown sheet connecting the upper edges of the fire box sheets, a smoke flue sheet spaced within and concentric to the second fire box sheet, said flue sheet and second fire box sheet being connected at their bottom edges to each other to provide an annular inner water leg, tubular members intersecting the upper part of the inner water leg and affording communication between the fire box and smoke flue, flow pipes connecting the lower parts of said water legs, a smoke pipe leading centrally down the smoke flue, means closing the space between the smoke pipe and the smoke flue sheet, a plate closing the lower end of said smoke flue, a fire clay tube surrounding the upper part of the smoke pipe, a closure plate at the lower end of the outer water leg and having a centrally disposed air inlet, and a damper controlling said inlet.

2. A vertical cylindrical boiler including an outer sheet, a fire box sheet concentric to and spaced from the outer sheet, the fire box sheet and outer sheet being connected at their bottom edges to provide an outer annular water leg, a second fire box sheet spaced inwardly from the first fire box sheet and concentric therewith, an annular crown sheet connecting the upper edges of the fire box sheets, a smoke flue sheet spaced within and concentric to the second fire box sheet, said flue sheet and second fire box sheet being connected at their bottom edges to each other to provide an annular inner water leg, tubular members intersecting the upper part of the inner water leg and affording communication between the fire box and smoke flue, flow pipes connecting the lower parts of said water legs, a smoke pipe leading centrally down the smoke flue, means closing the space between the smoke pipe and the smoke flue sheet, a plate closing the lower end of said smoke flue, a fire clay tube surrounding the upper part of the smoke pipe, a closure plate at the lower end of the outer sheet, a fire box sheet concentric to and air inlet, and a damper controlling said inlet.

3. A vertical cylindrical boiler including an outer sheet, a fire box sheet concentric to and spaced from the outer sheet, the fire box sheet and outer sheet being connected at their bot-

tom edges to provide an outer annular water leg, a second fire box sheet spaced inwardly from the first fire box sheet and concentric therewith, an annular crown sheet connecting the upper edges of the fire box sheets, a smoke flue sheet spaced within and concentric to the second fire box sheet, said flue sheet and second fire box sheet being connected at their bottom edges to each other to provide an annular inner water leg, tubular members intersecting the upper part of the inner water leg and affording communication between the fire box and smoke flue, flow

5 pipes connecting the lower parts of said water legs, a smoke pipe leading centrally down the smoke flue, means closing the space between the smoke pipe and the smoke flue sheet, a plate closing the lower end of said smoke flue, a fire clay tube surrounding the upper part of the smoke pipe, a closure plate at the lower end of the outer water leg and having a centrally disposed air inlet, a damper controlling said inlet, and burner tubes extending up within said fire box adjacent the outer water leg.

UEL R. GOODALE.
